Specification for Design.

Patented June 22, 1920.

Application filed February 11, 1920. Serial No. 357,818. Term of patent 7 years.

To all whom it may concern:

Be it known that I, GEORGE E. SHROPSHIRE, a citizen of the United States of America, residing at Yonkers, in the county of Westchester and State of New York, have invented and produced a new, original, and ornamental Design for a Decorative Paper, of which the following is a specification, reference being had to the accompanying drawing, forming a part thereof.

The drawing is a face view of a portion of the decorative paper showing my new design.

I claim:—

The ornamental design for a decorative paper as shown.

GEO. E. SHROPSHIRE.
